BUCKLE

John B. Freysinger, New Britain, Conn., assignor
to North & Judd Manufacturing Company, New
Britain, Conn., a corporation of Connecticut

Application October 19, 1932, Serial No. 638,504

1 Claim. (Cl. 24—191)

The present invention relates to buckles, and especially to buckles adapted to be used on the straps of conveyors, such as those employed in harvesters and similar farming implements. 5 Buckles of this kind are constrained to pass over pulleys, and the straps used in connection therewith are placed under great pulling strains which cause the teeth of the buckle to bite into the strap. Heretofore, the front cross bar of the 10 buckle which cooperates with the teeth of the buckle in holding the free end of the strap in place has been disposed close to the sharp ends of the teeth so that, in effect, this front cross bar acts as an anvil upon which one face of the 15 strap is held while the teeth of the buckle pierce the opposite face of the strap and cut the fibers of the material from which the strap is made. This cutting of the strap weakens it and the strap soon breaks under the strain placed upon it under 20 ordinary usage. The machine is then forced to be idle while a new strap is put on and the straps themselves are costly.

It is an object of the present invention to overcome the above noted disadvantages, and 25 with this thought in mind the present invention contemplates the provision of a front cross bar for the buckle which is provided with a plurality of recesses or notches disposed opposite to the teeth on the clamping plate of the buckle. 30 The provision of these recesses or notches forms spaces between the front cross bar and the adjacent face of the strap opposite the teeth on the clamping plate. This arrangement will permit the teeth to push aside the fibers of the 35 material from which the strap is made, without cutting the same and thereby mutilating and weakening the strap.

A further object of this invention is to provide 40 a buckle of this kind which comprises few parts, is simple in construction, is strong and may be cheaply manufactured.

Other objects will be in part obvious, and in part pointed out more in detail hereinafter.

The invention accordingly consists in the features of construction, combination of elements and arrangement of parts which will be exemplified in the construction hereinafter set forth and the scope of the application of which will be 50 indicated in the appended claim.

In the accompanying drawing, wherein is shown one embodiment which the present invention may take,

Fig. 1 is a top plan view of a strap with my improved buckle attached thereto;

Fig. 2 is a side elevation of the same;

Fig. 3 is a view similar to Fig. 1 with the free end of the strap removed;

Fig. 4 is a view taken on the line 4—4 of Fig. 3 and looking in the direction of the arrows; and

Fig. 5 is a perspective view of my improved buckle frame.

Referring more particularly to the drawing, my improved buckle comprises a frame generally designated A upon which is pivotally mounted 10 a clamping plate B adapted to cooperate with the frame A to grip the free end portion X of a strap therebetween. An attaching clip C is also pivotally mounted upon the frame A and is adapted to have secured thereto the other end 15 Y of the strap. A retaining loop D for the free end of the strap is provided and may be formed integral with the frame A.

The frame A includes a front bar 10, a rear bar 11 spaced from, and parallel with, said front 20 bar 10, and parallel spaced apart side bars 12 joining said front and rear bars together to form a substantially rectangular open frame.

The clamping plate B is pivotally carried by 25 the rear bar 11 of the member A so that it has swinging movement towards and from said member A with which it is adapted to cooperate to securely clamp therebetween the free end portion X of the strap in the desired adjusted position. The clamping plate B may be stamped 30 from a blank of sheet metal and has a substantially rectangular body portion 15 provided with a reduced rear end portion 16 which is rolled upon itself to form a knuckle by means of which the plate is pivotally secured to the rear bar 11 35 of the member A. The forward edge of the body portion 15 of the plate B is provided with a set of teeth 17 which are blunt and extend from the forward edge of, and in substantially the same 40 plane as, the body portion 15. The points of the teeth 17 terminate substantially at the inner side of the bar 10 of the member A. A second set of teeth 18 also extend from the forward edge of the body portion 15 and are interposed 45 between certain of the teeth 17. However, the teeth 18 are longer than the teeth 17 and are bent upwardly at an angle to the body portion 15 of the plate B. In order to provide sharp points to penetrate the strap, the tops of the teeth 18 50 at their free ends are beveled, as at 19. To limit the movement of the plate B toward the member A, the body portion 15 of the plate B is provided, at each side rearwardly of the teeth 17 and 18, with an upwardly inclined ear 55 20 adapted to seat upon its respective side bar 12

adapted to seat upon its respective side bar 12 55

of the member A when the plate B is in its lower-most position. Between the ears 20, and rearwardly of the teeth 17 and 18, the body portion of the plate B is provided with a transversely 5 extending rib 21 which imparts strength and rigidity to the plate in that region thereof which receives the maximum stresses and strains when the device is in use.

It will be noted that the teeth 17 are substantially V-shaped and the front bar 10 of the frame A is provided with a plurality of V-shaped recesses or notches 22. These recesses 22 are formed in the inner side and upper and lower faces of the bar 10 and each one of the recesses 15 is disposed opposite to a corresponding tooth 17 on the clamping plate B. It will be observed that the outerside of the bar 10 is provided with enlarged portions 23 disposed opposite to the recesses 22 so that the strength of the bar 10 20 will not be impaired by the formation of the recesses 22 therein. It is apparent from Figs. 2, 3, and 4 that, due to the provision of these notches 22, when the portion X of the strap is in place between the clamping plate there is 25 provided in the front bar 10 opposite the point of each tooth 17 a space, which spaces accommodate those portions of the strap end X which are engaged by the points of the respective teeth 17 so that these portions of the strap do not 30 contact the front bar 10. Since these portions of the strap do not bear against the bar 10, but are received by the recesses 22, there will be no cutting of the fibers of the material from which the strap is made. On the other hand, the fibers 35 of the strap material will merely be forced apart by the penetrating ends of the teeth 17. The teeth 18 are curved upwardly so that they pierce a portion of the strap which is disposed above the bar 10, as is clearly seen in Fig. 2, and hence 40 there is likewise no cutting of the strap fibers by the teeth 18.

The attaching clip C is preferably made from sheet metal and is substantially U-shape. The closed end portion of the U-shaped clip C is 45 provided with a pair of spaced apart knuckles 24 embracing the rear bar 11 of the frame A and by means of which the clip C has a pivotal mounting upon the frame A. The closed end of the clip C has, between its knuckles 24, a recess 25 which 50 receives the reduced end portion 16 of the plate B, and the knuckles 24 straddle the reduced end portion 16 of the plate B, whereby the plate B is held against substantial lateral shifting so that the teeth 17 will always be maintained in 55 registry with their respective recesses 22 of the bar 10. The legs of the U-shaped clip C are adapted to receive and house therebetween the end Y of the strap. Suitable aligned openings are provided in the clip C to receive rivets 26 60 or other fastening devices to hold the end Y of the strap in place between the legs of the clip.

The loop D may be formed integral with the frame A and comprises a pair of parallel arms 27 mounted on the frame A and a bar 28 supported by the arms 27. The bar 28 is parallel to the bar 11 of the frame A and cooperates with the bar 11 to hold the free end X of the strap in place after it has been passed upwardly between the bar 10 and the clamping plate.

The operation of the device is as follows: Assuming that the end Y of the strap has been properly secured to the clip C, as described above, and it is desired to adjust and secure the strap around the pulleys of a conveyor (not shown) the free end X of the strap is threaded under the bar 10 and upwardly through the frame member A against the teeth 17 and 18 over the body portion 15 of the plate B and then threaded through the loop D. The teeth 17 may be pushed firmly against the strap, and the teeth 18 may be forced firmly and securely into the strap by exerting a downward pressure on the ears 20 of the plate B.

The long sharp teeth 18 will pass completely 15 through and beyond the strap, and the blunt short teeth 17 will embed themselves in the material of the strap by pushing aside the fibers of the material of the strap. As pointed out above, each tooth 17 is disposed opposite a corresponding recess 22 in the bar 10 so that the portions of the strap opposite to that engaged by the teeth 17 are not forced against the bar 10 by the teeth 17 and thereby have its fibers cut by further pressure of the teeth 17. The recesses 25 22 of the bar 10 receive these portions of the strap and the teeth 17 merely push aside the fibers of the material of the strap so that when the teeth 17 are withdrawn from the strap these pushed aside fibers may return to their original 30 position and the strap is not mutilated or weakened. It is thus apparent that the life of the strap is prolonged and that shut downs of the machinery caused by strap breakage are greatly lessened, thereby effecting considerable saving 35 in time and money.

As many changes could be made in the above construction and many apparently widely different embodiments of this invention could be made without departing from the scope thereof, 40 it is intended that all matter contained in the above description or shown in the accompanying drawing shall be interpreted as illustrative and not in a limiting sense.

It is also to be understood that the language 45 used in the following claim is intended to cover all of the generic and specific features of the invention herein described and all statements of the scope of the invention which, as a matter of language, might be said to fall therebetween. 50

I claim as my invention:

In a buckle for straps, a frame having a cross bar and a front bar of circular cross section, said front bar being provided on its inner edge with a plurality of spaced apart recesses and a re- 55 inforcing enlarged portion on its outer edge in alignment with each recess, and a clamping plate of sheet metal pivotally mounted on said cross bar and having along its free edge a plurality of pointed long teeth adapted to extend over said front bar between said recesses, said plate also having a plurality of pointed short teeth alternating with said long teeth, the respective short teeth and recesses being complementary in shape and disposed in spaced apart relation and opposite one another and in substantially the same plane when the said plate is in clamping position. 60 65

JOHN B. FREYSINGER.
